UNITED STATES PATENT OFFICE.

WILLIAM H. HONISSL, OF HARTFORD, CONNECTICUT, ASSIGNOR OF ONE-HALF TO BEECH-NUT PACKING COMPANY, OF CANAJOHARIE, NEW YORK, A CORPORATION OF NEW YORK, AND ONE-FOURTH TO WILLIAM A. LORENZ, OF HARTFORD, CONNECTICUT.

APPARATUS FOR FEEDING TUBES.

1,118,551.

Specification of Letters Patent. Patented Nov. 24, 1914.

Application filed May 13, 1907. Serial No. 373,450.

To all whom it may concern:

Be it known that I, WILLIAM H. HONISSL, a citizen of the United States, and resident of Hartford, in the county of Hartford and State of Connecticut, have invented certain new and useful Improvements in Apparatus for Feeding Tubes, of which the following is a full, clear, and exact specification:

This invention comprises an apparatus for feeding various articles to which it may be found applicable.

The particular embodiment of the invention herein shown and described is adapted for the feeding of tubes made of flexible material, such as rubber, in connection with apparatus designed for cutting tubes into ring gaskets of a character suitable for use in making the closure joints of hermetically sealed jars and similar receptacles.

Figure 1 of the drawings is a front elevation of the machine. Fig. 2 is an end elevation projected from the left hand end of the machine of Fig. 1. Fig. 3 is a plan view in enlarged scale, and in section taken on the line 3—3 of Fig. 2. Fig. 4 is a fragmentary plan view also in section similar to that of Fig. 3, showing the valve of that figure in a different position. Fig. 5 is an end view in section taken on the line 5—5 of Fig. 3.

Fig. 6 is a section on the line 6 of Fig. 5. Fig. 7 is an end view of the clutch or coupler shown in Fig. 6. Fig. 8 is a plan view in section taken on the line 8—8 of Fig. 1. Fig. 9 is a plan view showing a modified form

35 of valve adapting the machine to the use of both high pressure and exhaust. Fig. 10 is a fragmentary view similar to a portion of Fig. 9 showing the valve in another position.

Fig. 11 is a side view showing a conventional 40 form of exhauster or pressure blower for use in conjunction with this invention. Fig. 12 is a front view in enlarged scale and in section on the line 12—12 of Fig. 2, showing the device for locking the slide to the feed bar. The direction in which the several sections are viewed are indicated by arrows placed adjacent to the respective section lines.

The improved apparatus feeds the tubes by intermittently holding and releasing the 50 interior and exterior surfaces of the tube by pneumatic pressure and advancing the tube while held by one side and released on the other side. In the operation of this appara-

tus the tube is passed through a receiver which approximately fits the exterior wall 55 of the tube, and a feeder which preferably consists of a cylindrical plunger, is placed within the tube approximately fitting the interior wall thereof, so that the tube occupies the annular space between the exterior 60 of the plunger and the interior of the receiver. The walls of the receiver and feeder adjacent to the tube are provided with air passages which are extended so as to communicate with any well-known or available 65 means for producing pneumatic pressure either by inducing a vacuum and thus utilizing atmospheric pressure, or by producing a pressure above that of the atmospheric, or using both these forms of pressure producing devices in conjunction, particularly 70 when it may be found desirable to utilize a pressure greater than that of the atmosphere. The pressure is applied intermittently and alternately to the interior and 75 exterior surfaces of the tube, and the latter is advanced while thus held either by the inner or outer side of the tube, and while released on the other side. In practice it is believed to be preferable to feed the tube 80 while held by its inner wall, the feed member or plunger being moved longitudinally to the desired extent while holding the tube, and while the outer surface of the tube is released from the receiver.

In the apparatus, which is shown and described herein, the tube 15 is within the conduit or receiver 16, and the tube carrier and feeder, which consists of a plunger 17 is within and concentric with the receiver, approximately fitting the interior wall of the tube. For convenience in adapting the apparatus for the manipulation of tubes of different sizes the receiver 16 is preferably made easily detachable, being, as herein 90 shown, removably attached to the spindle 18, which is mounted in any suitable way, as in the boxes or bearings 19 mounted in the head 20, which is or may be similar to the head of a lathe and may, for convenience in co-operating with tube cutting or other adjunctive mechanism, be mounted upon a bed 21. Any suitable means as a screw or screws 23 may be employed for removably holding the receiver 16 in position 95 in the spindle. By removing the screw the 100

receiver may be withdrawn and other receivers substituted of sizes and forms suited for the different tubes to be operated upon. In some instances in which this process of feeding and holding the tubes may be employed, it may be undesirable or unnecessary to rotate the tubes, in which case the receiver 16 and the plunger 17 need not be supported for rotative movement. But for many purposes, including the purpose of cutting tubes into gaskets, illustrated herein, it is desirable to rotate the tube. For this reason the spindle 19 is mounted for rotation, as herein shown and is provided with a pulley 24, or any other convenient means for imparting the rotative movement. In such cases also it is usually desirable to rotate the plunger 17 coincidently with the receiver. In the embodiment here shown the receiver and the plunger are mechanically clutched or coupled together by a coupling 25, which is fitted upon a hub 26 of the plunger and connected therewith by means of a spline 27, which serves to rotate the plunger with the coupling while permitting the longitudinal sliding movement of the plunger within the receiver and coupler. The coupling is preferably provided with an annular shoulder 29, which fits within the rearward end of the spindle 18 and centralizes the coupling and the plunger with that spindle.

As a means for insuring coincident driving engagement between the receiver and the coupling, one of them, in this instance the coupling, is provided with projections 30, which enter corresponding recesses 31 in the end of the receiver or the end of the spindle. The coupling being thus interlocked with the receiver and splined to the plunger, insures their coincident rotation.

For convenience in readily disconnecting the coupling to permit the withdrawal of the plunger from the receiver and the putting in of a new tube, the coupling is secured to the spindle by means of a screw-nut 33 which for convenience in handling may be provided with a handwheel rim 34. This nut is threaded upon the end of the spindle 18 and is provided with an inwardly projecting flange 35, which is interrupted at two or more portions preferably opposite each other to receive the outwardly projecting wings 36 of the coupling 25, these wings being preferably beveled, as shown by shade lines in Fig. 5, to insure easy engagement with the coengaging portions of the flange 35. By screwing the nut 33 in one direction the coupling 25 is clamped securely against the end of the spindle, while by turning the nut in the opposite direction to the position shown in Fig. 5 the coupling may be retracted, the wings 36 passing out through the coinciding interruptions in the flanges 35. For convenience and certainty

in turning the nut to this position it is provided with a pin 38 or similar projection extending into a slot 39 in the adjustable collar 40, which is clamped to the spindle in any convenient way as by the screw 41, and may be adjusted circumferentially so as to stop the nut at the removing position shown in Fig. 5. The slot 39 is extended annularly a sufficient distance to permit the nut to rotate far enough to insure clamping the coupling against the end of the spindle.

The surfaces of the receiver 16 and plunger 17, which are in contact with the outer and inner walls, respectively, of the tube, are adapted to serve as pneumatic grippers or holders coöperating to hold and advance the tube at the desired times and to the desired extent. The plunger, which in this instance is shown to be the feeding or advancing member, is provided with grooves 44 which are herein shown to extend circumferentially around the plunger and serve as passages for the air in forcing or inducing pneumatic pressure. These passages are connected in any convenient way through the rearward end of the plunger, either with exhausting apparatus or air compressing apparatus, which may be like that conventionally shown in Fig. 11. In the present instance, the plunger is mounted for rotation upon a non-rotating spindle 45, which is provided with an air passage 46 extending longitudinally within the spindle to the rearward end thereof. At its front end the air passage 46 communicates outwardly by means of the air holes 47 and circumferential grooves 48 with the continuing passages 49 leading to the circumferential grooves 44 on the outer surface of the plunger, thus affording continuous air communication between the latter grooves and the air duct or conduit 46, whether the plunger is rotating or stationary. These grooves are herein shown to be only two in number and situated only at the front end of the plunger, since it is desirable in this particular case to grip the tubes at that end, so that the tubes may be fed forward nearly their entire length before their rearward ends reach and uncover these grooves. Obviously however, the grooves may be extended farther over or completely over the surface of the plunger. The receiver 16 is also shown to be provided with circumferential air grooves 51, which for the reason just given are also preferably limited to the front end of the receiver. These grooves communicate with the longitudinal groove or grooves 52 which may extend to the rearward end of the receiver, or may, as herein shown, communicate with an annular recess 53 in the interior of the spindle, or the exterior of the receiver. At its rearward end the recess communicates with the air duct 54, which extends to the end of the spindle and com-

5 municates with a duct 55 of the coupling 25, air-tight connection being insured if necessary by means of a rubber washer or gasket 56. At its inner end the duct 55 extends into communication with the duct 57, which 10 communicates with the circumferential groove 58, which may be in the interior wall of the hub 26, or as herein shown, in the exterior surface of the spindle 45, thence 15 extending through the cross duct 59 and longitudinal duct 60, to the end of the spindle; and thence to the exhaust or pressure producing means.

20 The spindle 45 is supported at its rearward end by a spindle head 62; and the ducts 46 and 60 which communicate independently of each other with the air grooves 44 and 51 of the plunger and receiver, respectively, are extended through the spindle support 25 62; and their connection with the air exhausting or compressing apparatus, as the case may be, is controlled by means of a valve 65, the construction and operation of which will be hereinafter more particularly described.

30 The description thus far given relates to a single receiver 16 and a single plunger 17, and this receiver may be efficiently served by such a single plunger, which after feeding one tube as far as it will go can be withdrawn from the receiver and a succeeding tube be inserted. But to expedite the operation of the device by lessening the time during which its feeding operations are interrupted, I preferably provide a plurality of these plungers, so that while one plunger is performing its feeding operations another plunger may have a new tube mounted upon it in readiness for the next feeding 40 operation. Any desired number of these plungers may be employed. I have, however, shown herein but two plungers, extending in opposite directions from the support 45 62, which thus becomes a sort of monitor or turret head, which is mounted for rotation upon a stud 66, which is clamped or otherwise secured in the sliding head 67 mounted on the feed bar 68. The spindles 45 are secured to their supporting monitor 50 62 in any convenient way. The plungers 17 are mounted on these spindles, being held against endwise movement by suitable collars or shoulders 70 and 71. Washers 72 of rubber or leather, may, if desired, be 55 inserted between the ends of the plunger and its end bearing collars or shoulders to make these joints more nearly air-tight.

60 The head 67 for supporting the monitor 62 is mounted for longitudinal movement in a direction parallel with the longitudinal center line of the receiver. As herein shown the monitor head is supported upon a feed bar 68, which is mounted for sliding movement in any convenient way, as upon the 65 front side of the head 20 (Figs. 1 and 2).

For convenience in allowing the head 68 to be drawn backwardly so as to retract the forward plunger 17 from the receiver without also drawing the feed bar backwardly, the head is fitted for sliding movement upon the feed bar, so that it may be drawn back to its dot-and-dash line position shown in Fig. 1. When in its forward or feeding position shown in full lines in that figure, the head abuts against a stop 75 and is 70 locked in that position by any suitable means, shown to consist of a mutilated cylindrical bolt 76, which when turned to the position shown in Figs. 1 and 12 locks the head 67 in feeding position; but when 75 turned about 180 degrees from the position shown in Figs. 1 and 12 brings the recessed portion 77 of the bolt into the pathway of the feed bar 68, thus unlocking the head and permitting it to be slid back and forth, 80 this movement being generally and preferably effected by hand.

85 As a convenient means for automatically reciprocating the feed bar 68 to impart the longitudinal feeding movements to the plunger 45, the machine is herein shown to be provided with a cam 80, which is mounted upon a cam shaft 81 mounted for rotation in suitable bearings 82, herein shown to be appurtenant to the bed 21 of the machine. 90 This cam shaft may be driven from some other portion of the machine, or it may be driven independently by means of a belt pulley 83. The peripheral groove 84 of the cam 80 engages with a roller or pin 85 appurtenant to the feed lever 86, which is pivotally mounted at 87, the contour of the cam groove 84 being suited for imparting the required movements to the lever 86. In order to vary the amplitude of movement 95 of the feed bar 68 so as to correspondingly vary the extent of feed of the tube, the driving connection between the lever 87 and the feed bar 68 is in the form of a slotted cross head. The upper portion of the lever 100 86 is provided with a slot 88 (see Figs. 1 and 8) in which a connecting pin 89 is mounted for longitudinal movement, being secured at any desired portion lengthwise of the slot by means of a nut 90 and washer 91. 105 To facilitate the accurate setting of the connecting pin to the several positions required for predetermined amounts of feed, the surface of the lever 87 is provided with suitably graduated marks 92 which may be 110 read in conjunction with a zero mark upon the washer 91, the edge of which may be beveled so as to be read more easily. The rearward cylindrical end of the connecting pin 89 fits in a sliding block 94 which is 115 fitted in sliding ways in the crosshead 95 appurtenant to the feed bar 68 (Fig. 8).

120 In most cases it will be found desirable to have the plunger 17 come to a uniform position at the forward end of its stroke, 125 130

whatever may be the variations in the length of the stroke, confining those variations to the rearward end of the stroke. In the present instance this is accomplished by making the slot 88 of the feed bar 86 coincident in position with the slide-way for the block 94 in the cross head 95, when these parts are in their forward position shown in Fig. 1, in which coinciding position it will be found most convenient to make the adjustments of the connecting pin 89.

The flow of air to and from the receiver 16 and plunger 17 through the ducts 60 and 46, respectively, which determine the application of the pneumatic pressure, is controlled by means of the valve 65, which is preferably of a cylindrical form and is mounted for sliding movement in the stud 66, as shown by a comparison of the position of the valve in Figs. 3 and 4. In the arrangement shown in Figs. 3 and 4 it is assumed that the pressures are produced either by exhaustion alone, or compression alone,—not by a combination of both.

The end of the valve 65 is connected with any suitable exhaust or pressure producing apparatus like that shown in Fig. 11, by means of a tube 98 which is either jointed or flexible to permit of the longitudinal and transverse movements of the valve. The duct 99 extends from the tube 98 through the outwardly opening passage or passages 100 to the distributing passage 101, which when in the position shown in Fig. 3 communicates with the duct 60 leading to the receiver 16; and when in the other position shown in Fig. 4 communicates with the duct 46 leading to the plunger 17. Relief passages 102 and 103 are preferably provided in the valve 65 connecting either of the passages 60 or 46 with the open air when the other of those passages is in communication with the distributing passage 101.

In order to operate the valve 65 while permitting it to be moved back and forth with the longitudinal movements of the plunger 17, the front end of the valve is connected with a valve lever 105 mounted on the rock shaft 106 which is journaled for rocking movement with its axis in a parallel relation to the feed bar 68 and the receiver 16. The shaft is rocked by means of an arm 107 pivotally connected to the connecting rod 108, the opposite end of which is pivotally connected to a cam arm 109 which is mounted upon a pivot stud 110 and is provided with a pin or roll 111 engaging in a cam groove 112 of the valve cam 113 mounted upon or driven by the cam shaft 81. The pathway 112 of the cam is of a contour suited for producing the desired movements of the valve 65 back and forth between its two positions shown in Figs. 3 and 4. In order to enable the valve lever 105 to remain in operative engagement with the valve 65 dur-

ing the longitudinal movements of the plunger 17 and its monitor head 62 that valve lever is mounted between suitable end bearings 115 of the sliding head 67, being thereby made to slide longitudinally upon its rock shaft 106, while remaining in driving engagement with that shaft by means of a key or spline sliding in a suitable splineway 116 of the shaft.

In order to illustrate one of the useful applications of this invention, the machine is herein shown to be provided with a cutting apparatus for cutting rings from the end of the tube as the latter is intermittently projected beyond the end of the receiver 16 and feeder 17. Various instrumentalities may be thus employed for cutting off these rings. I have, however, herein shown in a general way an apparatus which has been devised for this purpose and which is shown, described and claimed in co-pending applications of the present applicant and another. That portion of said apparatus which is shown herein consists of a rotating disk cutter 118 which is mounted upon a suitable spindle 119 rotating in suitable bearings 120 and provided with a pulley 121 driven by a belt 122 from overhead shafting or in any other convenient way. The bearings are supported by suitable slides and swivels which enable the cutter to be swung to any desired angle relative to the tube, and to be reciprocated so as to carry the edge of the cutter through the wall of the tube in a line 123 coinciding with the desired angle of the cut. The mechanism by which the desired sliding movement is effected is contained in the cutter-head designated in a general way by 124 and is driven by a suitable shaft by means of the bevel gear 125, which in turn is driven by the bevel gear 126 splined upon the cam shaft 81, but journaled in the depending bracket 127. Being thus driven by the shaft 81 the cutter head and its mechanism may be operated in proper synchronism with the cams 80 and 113, which control the actuations of the feeding mechanism and its pressure valve. It is not considered necessary to give a detailed description or drawing of this cutting mechanism, since its details form no part of the present invention, and other forms of apparatus might be substituted for cutting off the rings, or for performing any other desired operation upon the tubes in conjunction with the feeding mechanism, which is the subject matter of the present application.

The operation of this apparatus is as follows:—The plunger 17 being withdrawn from the receiver, the tube is placed in position upon the plunger and the latter is carried forward by pushing the sliding head 67 forward against the stop 75 of the feeding bar and locating it in that position by means of the bolt 76. The coupling 25 is then ad-

justed to its seat against the end of the receiver 16 and its spindle 18; and is fastened to that position by means of the clamp nut 33. The forward feeding movement then begins. Assuming that the tube 98 is connected with exhausting apparatus, the valve 65 when in the position shown in Fig. 3 directs the exhaust to take effect through the duct 60 and the grooves or recesses 51 of the receiver, while permitting atmospheric pressure to enter through the relief passage 102 and duct 46, thus holding the tube outwardly against the inner wall of the receiver 16 and releasing the plunger 17. The latter is then drawn backwardly to the required extent by the operation of the rotating cam 80. When the plunger reaches its rearward resting position the valve 65 is moved to the position shown in Fig. 4, thus connecting its distributing passage 101 with the duct 46 and grooves 44 of the plunger and at the same time admitting atmospheric pressure through the ducts 103 and 60 to the grooves 51 of the receiver, thus pressing the tube inwardly against the plunger and releasing it from the receiver. The width of the distributing passage 101 of the valve relative to the ducts 46 and 60 is such that when the valve is moved from one position to the other, the exhaust takes full effect upon one of those ducts before being shut off from the other duct; or at least before atmospheric pressure is admitted to the other duct, so as to retain the tube at all times under control of the pressure, gaining a hold on one side or portion before releasing the other side or portion. With the tube thus held against the plunger 17 the latter is moved forwardly by its cam, thus projecting the leading end of the tube beyond the front end of the feeder and receiver, where the parts remain while the gasket ring is being severed, or otherwise operated on, as shown in Fig. 3. Then the valve 65 is moved again to the position shown in Fig. 3, pressing the tube away from the plunger and against the receiver to permit the plunger to be again retracted without also retracting or otherwise moving the tube. Thus the forward feeding movements are continued intermittently and alternately, and also in alternation with the operations of the cutter for cutting off the end of the tube. When finally the rearward end of the tube passes to or beyond the grooves 51 and 44, and the feeding stops, the screw nut 33 is turned to the position shown in Fig. 5, and the coupling 25 is withdrawn as shown in Fig. 6. Then the sliding head 67 is unlocked from the feed bar 68 by turning the bolt 76, and is drawn backwardly to withdraw the plunger 17 from the receiver. In the case of a machine having but a single plunger 17 a new tube is then placed in position, the parts are again pushed forward and coupled to the receiver, and the feeding movement is

again resumed. In the case of a machine having a plurality of plungers 17 upon a swinging turret or monitor head 62, the spindle which is out of feeding operation is supplied with a new tube while the other plunger is feeding its tube forward, the monitor head being turned upon its supporting stud 66 when the sliding head 67 is retracted so as to bring the plunger carrying the new tube into alinement with the receiver. 70 75

In the case of a machine operated by compressed air the operation is quite similar; the principal difference being in the position of the valve 65, which is the reverse of that required for operating by exhaust and atmospheric pressure. In other words, when employing compressed air the valve 65, when in the position shown in Fig. 3, admits the pressure through the receiver to the outer side of the tube, holding the latter against the plunger 17 and continues thus to hold it during the forward feeding movement of the plunger, after which the valve is shifted to the position shown in Fig. 4 which admits pressure through the ducts 46 and 44 to the inner side of the tube, holding it outwardly against the receiver and thus releasing the plunger which is then drawn back. In this case the relief ducts 102 and 103 operate to release the pressure from each of the ducts 46 and 60 when the other of those ducts receives the pressure. 80 85 90 95

During the time that the projecting tube is being operated upon by the cutter or other means, it may be held either to the plunger 17 or to the receiver 16 as may be found most convenient or desirable, according to the character of the operation and the direction in which it is applied. In the present instance, in which the cutter penetrates the tube from its outer side and hence tends to press the tube inwardly, it is considered preferable to hold the tube inwardly against the surface of the plunger while being cut. 100 105 110

The modification shown in Figs. 9 and 10 adapts the machine to employ exhaust and atmospheric pressure in connection with what may be here termed "super-atmospheric pressure" or air compressed above atmospheric pressure. The modification is confined to the valve itself which has a double ended connection, one end being connected with exhausting apparatus, and the other end with compressing apparatus, either or both of which may be of the type represented in a general way by Fig. 11, the characteristic differences between exhaust and pressure blowers being well understood. As this modification is shown, 115 the valve 130 is provided with flexible or jointed tubes 131 and 132, one leading to pressure and the other to exhaust apparatus. For definiteness in description it is herein assumed that the tube 131 connects with an ex- 120 125 130

haust apparatus, while the tube 132 connects with air compressing apparatus. The duct 133 leads from the tube 131 to the distributing passage 134, these being similar in arrangement to the corresponding ducts and passages of the valve 65 shown in the previous figures. The front or compression end 5 of the valve 130 is provided with a duct 136, which leads from the tube 132 to two distributing passages 137 and 138. The relation of these distributing passages to each other and to the ducts 46 and 60 of the plungers and receivers, during the movements of the valve, is shown by comparison 10 of Figs. 9 and 10. In Fig. 9 the duct 60 leading to the receiver is in communication with the exhaust, while the duct 46 leading to the plunger is in communication with the high pressure or compressing apparatus, 15 thus serving to hold the tube outwardly against the receiver, with a pressure which is determined by the pressure delivered by the air compressing device, and may be varied to suit different conditions. Upon 20 moving the valve to the position shown in Fig. 10, the holding conditions are reversed, the duct 46 leading to the plunger being then connected with the exhaust, while the duct 60 leading to the receiver is connected 25 with the pressure, thus pressing the tube against the plunger, at which time the plunger is given its forward feeding movement to advance the tube.

When using the simple exhaust plan the 30 pressure is obviously limited to that of the atmosphere, whereas by using forced pressure it may be increased to any extent likely to be found necessary. Although for many purposes the arrangement shown in Figs. 3 35 and 4, employing what may be termed a "single" or "simple" pressure, will be found sufficient for holding and feeding tubes with certainty and uniformity; for some other purposes it may be found desirable to employ the double acting method 40 shown in Figs. 9 and 10. To effect the change from one to the other it is only necessary to remove the valve 65 from the apparatus and replace it with the valve 130, 45 the length of stroke and time of operation as herein arranged being the same. The cams 80 and 113 are suited for operating the double-acting modifications shown in Figs. 9 and 10, as well as the single acting 50 form shown in Figs. 3 and 4.

The valve shown in Figs. 9 and 10 is adapted like that shown in Figs. 3 and 4 to gain a hold on one side of the tube before releasing its hold on the other side of the 55 tube. This is due to the spacing and lapping of the valve passages relative to the ducts 46 and 60.

The monitor or turret 62 may have any 60 desired number of arms. It may be mounted upon a vertical axis so as to revolve the

arms in a horizontal plane. But for the purposes now under contemplation it is considered sufficient to have two plungers mounted diametrically opposite to each other upon the monitor head 62, and is considered preferable to swing the plungers in a vertical plane. 70

Under some conditions, or for some purposes, it may be found preferable to impart the advancing movement of the tube by 75 means of the receiver, using the plunger as the stationary holding member, and sliding the receiver forward and back in its bearings, instead of sliding the plunger as herein shown and described. It may also in 80 some cases be found sufficient to dispense with the air grooves and passages in the receiver or whichever may be the stationary member. In that case the tube may fit the stationary member somewhat closely, so as 85 to hold thereto by friction, while the feed member is being retracted to get a new hold. But for most purposes I prefer to employ air pressure alternately on opposite sides 90 of the tube.

The term "super atmospheric" is for convenience and brevity herein employed to designate pressures above that commonly designated as atmospheric pressure, the latter of which at no time reaches fifteen 95 pounds per square inch, and varies below that according to the degree of exhaustion or vacuum by which it is induced, whereas super atmospheric pressure, obtained by compressing the air in any of several well-known ways, may be carried to any degree 100 likely to be desired.

The process which is carried out by the apparatus shown herein forms the subject matter of a divisional application, Serial 105 No. 573,858, filed July 26, 1910.

I claim as my invention:—

1. The combination, in tube feeding mechanism, of a pneumatic gripping device for holding the tube, a movable pneumatic feeding device for advancing the tube, means for alternately operating said devices to grip and release the tube, and means for moving the said feeding device while it grips the tube. 110

2. Means for feeding tubes, including a plurality of pneumatic grippers for the tube, means for moving one of said grippers to feed the tube bodily forward, and means for alternately interrupting and restoring the 115 pneumatic holding action of the said grippers in coöperation with the tube feeding movements.

3. Means for feeding tubes, including a support for the tube provided with pneumatic means for holding the tube, a pneumatic gripper, means for moving the gripper to advance the tube relative to its support, and means for interrupting and restoring the pneumatic action of the support and 120

the gripper in suitable time relation to the advancing movements of the tube.

4. Means for feeding tubes, including in combination a tube support, provided with pneumatic means for holding the tube, a gripper provided with pneumatic means for holding the tube, means for moving the gripper to advance the tube relative to its support, and means for interrupting and restoring the pneumatic action of the tube support and the gripper in proper time relation to the advancing movements of the tube.

5. Means for feeding tubes, including in combination pneumatic holding devices for the inner and outer walls of the tube, means for moving one of said holding devices relative to the other to advance the tube, and means for interrupting and restoring the pneumatic action of the said devices to grip the tube alternately to the said holders in proper time relation to the advancing movements of the tube.

6. Means for feeding tubes, including in combination a support encircling the outer wall of the tube, a plunger within the tube in approximate engagement with its inner wall, pneumatic means for holding the tube alternately to the support and to the plunger, and means for moving the plunger in proper time relation to the said pneumatic holding means.

7. The combination, in tube feeding mechanism, of pneumatic gripping devices for the exterior and interior, respectively, of the tube, means for moving one of said gripping devices relative to the other to advance the tube, and means for applying the pneumatic gripping action intermittently in proper time relation to the advancing movements of the tube.

8. The combination, in tube feeding mechanism, of pneumatic gripping devices for the exterior and interior, respectively, of the tube, means for moving one of said gripping devices relative to the other to advance the tube, and means for applying the pneumatic gripping action intermittently, and alternately to the respective gripping devices, in proper time relation to the desired advancing movements of the tube.

9. The combination, in tube feeding mechanism, of a cylindrical receiver for the exterior of the tube, a cylindrical plunger for the interior of the tube, means for applying pneumatic pressure intermittently to hold the tube alternately to the receiver and to the plunger, and means for moving the plunger relative to the receiver to advance the tube.

10. The combination, in tube feeding mechanism, of a cylindrical receiver approximately fitting the exterior of the tube, a cylindrical plunger approximately fitting the interior of the tube, means for applying

pneumatic pressure intermittently to hold the tube alternately to the receiver and to the plunger, and means operating synchronously with the operation of the pneumatic devices for moving the plunger in one direction when the tube is held thereto, and in the opposite direction when released from the tube.

11. The combination, in tube feeding mechanism, of a receiver approximately fitting the exterior of the tube, a plunger approximately fitting the interior of the tube, means for holding the tube by pneumatic pressure alternately to the receiver and to the plunger, and means for reciprocating the plunger synchronously with the operation of the pneumatic holding means, moving in one direction when the tube is held to the plunger and in the opposite direction when the tube is held to the support.

12. The combination, in tube feeding mechanism, of a rotary receiver approximately fitting the exterior of the tube, means for holding the tube to the receiver by pneumatic pressure, and means for establishing and interrupting the pneumatic communication with the rotating receiver.

13. The combination, in tube feeding mechanism, of a rotary receiver approximately fitting the exterior of the tube, means for holding the tube to the receiver by pneumatic pressure, means for producing the pneumatic pressure, and means for establishing and interrupting the pneumatic communication between the pressure producing means and the rotating receiver.

14. The combination, in tube feeding mechanism, of a rotary receiver for the exterior of the tube, a plunger mounted within the tube for rotation with the receiver, means for producing pneumatic pressure, and means for establishing and interrupting the pneumatic communication between the pressure producing means and the rotating plunger.

15. The combination, in tube feeding mechanism, of a pneumatic receiver and holder for the exterior of the tube, a pneumatic feeder within the tube, and means for establishing and interrupting the pneumatic action of the holder and feeder in alternation.

16. The combination, in tube feeding mechanism, of a rotary receiver for the exterior of the tube, a pneumatic feeder within the tube, means for producing pneumatic pressure, and means for establishing and interrupting pneumatic communication between the pressure producing means and the receiver and feeder in alternation.

17. The combination, in tube feeding mechanism, of a rotary receiver for the exterior of the tube, a rotary plunger within the tube, pneumatic pressure producing means, air passages leading from the pressure produc-

- ing means to the tube engaging surfaces of the receiver and plunger, respectively, and means for directing the pressure relative to the receiver and the plunger.
18. The combination, in tube feeding mechanism, of a rotary receiver for the exterior of the tube, a rotary plunger within the tube, pneumatic pressure producing means, air passages leading from the pressure producing means to the tube engaging surfaces of the receiver and plunger respectively, means for directing the pressure relative to the receiver and the plunger, and means for reciprocating the plunger, to advance the tube when it is held to the plunger by the pressure and to retract the plunger when the tube is released therefrom.
19. The combination, in tube feeding mechanism, of a rotary receiver for the exterior of the tube, a rotary plunger within the tube, pneumatic pressure producing means, air passages leading from the pressure producing means to the tube engaging surfaces of the receiver and plunger respectively, and means for directing the pressure relative to the receiver and the plunger, means for reciprocating the plunger to advance the tube, and means for operating the valve synchronously with the reciprocations of the plunger to press the tube against the plunger while the latter is moved in one direction, and to release it therefrom when moved in the other direction.
20. The combination, in tube feeding mechanism, of a rotary receiver for the exterior of the tube, a rotary plunger within the tube, pneumatic pressure producing means, air passages leading from the pressure producing means to the tube engaging surfaces of the receiver and plunger respectively, means for directing the pressure relative to the receiver and the plunger, means for operating the valve, and means for reciprocating the plunger in proper time relation to the operation of the valve, advancing the plunger and tube when they are pressed together and retracting the plunger when they are released.
21. The combination, in tube feeding mechanism, of a rotary receiver for the exterior of the tube, a rotary plunger within the tube, pneumatic pressure producing means, air passages leading from the pressure producing means to the tube engaging surfaces of the receiver and plunger respectively, means for directing the pressure alternatively to the receiver and the plunger, means for operating the valve, and means for reciprocating the plunger to advance the plunger when the tube is pressed against it, and to retract the plunger when the tube is pressed against the support.
22. The combination, in mechanism for making ring gaskets, of pneumatic gripping devices for advancing and holding the tube, and cutting devices for severing rings successively from the advanced tube.
23. The combination, in a gasket cutting machine, of means including pneumatic gripping devices for holding and intermittently advancing the tube, and means for cutting the gasket rings successively from the advanced tube.
24. The combination, in a gasket cutting machine, of means including a pneumatic gripper for holding and intermittently advancing the tube, and means for cutting the ring gaskets successively from the tube during the intermissions in the advancing movement of the tube.
25. The combination, in a gasket cutting machine, of a rotary receiver for the gasket tubes, pneumatic gripping devices for intermittently advancing and holding the tube, and means for cutting the ring gaskets in succession from the tube.
26. The combination, in a gasket cutting machine, of a rotary receiver for tubes of gasket material, pneumatic gripping devices for holding and intermittently advancing the tube, and means for cutting the gasket rings in succession from the tube in alternation with the advancing movement of the tube, and during the intermissions in that movement.
27. The combination, in a gasket cutting machine, of a rotary receiver for tubes of gasket material, pneumatic gripping devices, including a rotary feeder within the tube, for holding and intermittently advancing the tube, and means for cutting the gasket rings in succession from the tube in alternation with the advancing movements of the tube, and during the intermissions in the said movement.
28. The combination, in tube feeding mechanism, of a rotary receiver for the exterior of the tube, a rotary plunger for the interior of the tube, air passages leading from the tube engaging surfaces of the receiver and plunger to a non-rotating central member, pneumatic pressure producing means, and means as a valve for selectively establishing communication between the pressure producing means and the said air passages.
29. The combination, in tube feeding mechanism, of a rotary receiver for the exterior of the tube, a rotary plunger for the interior of the tube, a central non-rotating member, air passages connecting the said rotary members with air passages of the said non-rotating member, and means for controlling the distribution of pneumatic pressure in the rotary members, through the air passages of the said non-rotating member.
30. The combination, in tube feeding mechanism, of a rotary receiver for the exterior of the tube, a feeder for the interior of the tube, a non-rotating member upon which the feeder is mounted for rotation,

independent air passages extending from the tube engaging surfaces of the receiver and plunger to and through the central member, and means for controlling the distribution of air pressure to the said independent passages.

31. The combination, in tube feeding mechanism, of a rotary receiver for the exterior of the tube, a plunger for the interior of the tube, air passages connecting with the tube engaging surfaces of the receiver and plunger, a non-rotating member provided with ducts communicating independently with the said air passages of the receiver and plunger, and means as a valve for directing the pressure to the ducts of the non-rotating member whereby the said pressure is distributed to the said rotating plunger.

32. The combination, in tube feeding mechanism, of a rotary receiver for the exterior wall of the tube, a plunger for the interior of the tube, a coupling connecting the receiver and plunger to cause them to rotate together, pneumatic pressure producing means, and air passages connecting the receiver with the said pressure producing means through the said coupling.

33. The combination, in tube feeding mechanism, of a rotary receiver for the outer wall of the tube, a plunger for the inner wall of the tube, a coupling connecting the receiver and plunger to cause them to rotate together, and means for attaching the coupling to and detaching it from the receiver to facilitate withdrawing the plunger from the receiver.

34. The combination, in tube feeding mechanism, of a rotary receiver for the outer wall of the tube, a plunger for the inner wall of the tube, a spindle on which the plunger is mounted for rotation, and a coupling member connecting the plunger and the receiver to cause them to rotate together.

35. The combination, in tube feeding mechanism, of a rotary receiver for the outer wall of the tube, a plunger for the inner wall of the tube, a spindle on which the plunger is mounted for rotation, and a clutch member connecting the plunger and the receiver to cause them to rotate together, the spindle being provided with air ducts leading to the plunger and to the receiver, respectively.

36. The combination, in tube feeding mechanism, of a receiver for the outer wall of the tube, a plunger for the inner wall of the tube, a spindle on which the plunger is mounted for rotation, and a clutch member connecting the plunger and the receiver at their rearward ends to cause them to rotate together, the spindle being provided with air ducts leading independently of each other to the plunger and the receiver, respectively.

37. The combination, in tube feeding mechanism, of a rotary receiver for the outer

wall of the tube, a plunger for the inner wall of the tube, a spindle supporting the plunger for rotation concentrically with the receiver, and a clutch connecting the receiver and the plunger for coincident rotation.

70

38. The combination, in tube feeding mechanism, of a rotary receiver for the outer wall of the tube, a plunger for the interior of the tube, a spindle supporting the plunger for rotation concentrically with the receiver, and a clutch connecting the receiver and the plunger for coincident rotation, the said spindle and clutch being provided with air ducts leading independently to the plunger and receiver, respectively.

75

39. The combination, in tube feeding mechanism, of a rotary receiver for the outer wall of the tube, a plunger for the interior of the tube, a spindle supporting the plunger for rotation concentrically with the receiver, and a clutch connecting the receiver and the plunger for coincident rotation, the said spindle being provided with independent air ducts one of which communicates with the tube engaging surface of the spindle and the other of which communicates through the said clutch with the tube engaging surface of the receiver.

80

40. The combination, in tube feeding mechanism, of a rotary receiver for the outer wall of the tube, a plunger for the interior of the tube, a spindle supporting the plunger for rotation concentrically within the receiver, and means for closing the joint between the receiver and plunger at their rearward ends.

85

41. The combination, in tube feeding mechanism, of a rotary receiver for the outer wall of the tube, a plunger for the interior of the tube, a spindle on which the plunger is mounted for rotation concentrically with the receiver, a coupling member appurtenant to the plunger, and means for attaching the coupling member to and detaching it from the receiver to facilitate the withdrawal and replacing of the plunger.

90

42. The combination, in tube feeding mechanism, of a rotary receiver for the outer wall of the tube, a plunger for the interior of the tube, a spindle on which the plunger is mounted for rotation concentrically with the receiver, and means appurtenant to the plunger for coupling the receiver and the plunger for coincident rotation and making a close joint between them.

100

43. The combination, in tube feeding mechanism, of a rotary receiver for the outer wall of the tube, a plunger for the interior of the tube, a spindle supporting the tube for rotation concentrically within the receiver, a coupling connecting the receiver and plunger at their rearward ends, and closing the joint between them, and means for connecting the coupling with and disconnecting it from the receiver.

120

125

130

44. The combination, in tube feeding mechanism, of a rotary receiver for the outer wall of the tube, a plunger for the interior of the tube, a spindle supporting the tube for rotation concentrically within the receiver, a clutch member connecting the receiver and plunger at their rearward ends, and closing the joint between them, and means including a screw nut for clamping the clutch member to the receiver and releasing it therefrom.

45. The combination, in tube feeding mechanism, of a rotary receiver for the outer wall of the tube, a plunger for the interior of the tube, a spindle supporting the tube for rotation concentrically within the receiver, a coupling connecting the receiver and plunger at their rearward ends, and closing the joint between them, and means including a mutilated screw nut for clamping the said clutch member to and releasing it from the rearward end of the receiver.

46. The combination, in tube feeding mechanism, of a rotary receiver for the outer wall of the tube, a plurality of plungers for the interior wall of the tube, means for supporting either of said plungers in coactive relation with the said receiver, pneumatic pressure producing devices, and air passages connecting the said pressure producing devices with the tube engaging surfaces of whichever plunger is in coactive relation to the receiver.

47. The combination, in tube feeding mechanism, of a rotary receiver for the outer wall of the tube, a plurality of plungers for the interior of the tube, means for supporting either of said plungers for rotation in concentric relation to the receiver, and means for coincidentally rotating the receiver and the plunger which is in concentric relation to the tube.

48. The combination, in tube feeding mechanism, of a rotary receiver for the outer wall of the tube, a plurality of plungers for the interior wall of the tube, means for supporting either of said plungers for rotation in coactive relation to the receiver, and means for coincidentally rotating the receiver and the plunger which is in coactive relation therewith, and means for establishing air communication between the tube engaging surfaces of the receiver and plunger and pneumatic pressure producing devices.

49. The combination, in tube feeding mechanism, of a receiver for the tube, a plurality of tube carriers, means for supporting the said carriers for rotation and moving them successively into alignment with and inserting them in the receiver.

50. The combination, in tube feeding mechanism, of a receiver for the tubes, a plurality of tube carriers, means for supporting the said carriers and moving them

successively into the said receiver, and means for establishing air communication between the tube carrier and its support when the carrier is in the receiver.

51. The combination, in tube feeding mechanism, of a tube receiver, a plurality of tube carriers, means for supporting the said carriers and inserting them successively in the said receiver, and means for establishing air communication between the said receiver and the carriers as they are successively inserted in the receiver.

52. The combination, in tube feeding mechanism, of a tube receiver, a plurality of tube carriers, means for supporting the carriers for selective insertion in the receiver, and means for coupling the receiver and the selected carrier together, including means for coupling them for air communication.

53. The combination, in tube feeding mechanism, of a tube receiver, a plurality of tube carriers, means for supporting the plurality of carriers for selective insertion in the receiver, and means for establishing mechanical and pneumatic connection between the receiver and each of the selectively inserted carriers.

54. The combination, in pneumatic holding and feeding mechanism for tubes, of a tube carrier provided with an air duct, a monitor head revolubly supporting the carrier, and a pivotal support for the monitor head provided with an air duct registering with the said air duct of said tube carrier when the latter is in its feeding position.

55. The combination, in pneumatic holding and feeding mechanism for tubes, of a tube carrier provided with a plurality of air ducts, a monitor head revolubly supporting the carrier, and a pivotal support for the monitor head provided with air ducts registering with the said air ducts of said tube carriers when the latter is in its feeding position.

56. The combination, in pneumatic holding and feeding mechanism for tubes, of a plurality of tube carriers each provided with an air duct, a monitor head revolubly supporting the carriers, and a pivotal support for the monitor head, provided with an air duct registering with the air ducts of the respective carriers when each is at its feeding position, and being out of register with the said ducts when the carriers are out of their feeding position.

57. The combination, in pneumatic holding and feeding mechanism for tubes, of a tube carrier provided with an air duct, a monitor head revolubly supporting the carrier, a pivotal support for the monitor head provided with an air duct registering with the said air duct of said tube carrier when the latter is in its feeding position, and a valve mounted in the pivotal support for

controlling the flow of air through the said ducts.

58. The combination, in pneumatic holding and feeding mechanism for tubes, of a tube carrier provided with an air duct, a monitor head revolubly supporting the carrier, a pivotal support for the monitor head provided with an air duct registering with the said air duct of said tube carrier when the latter is in its feeding position, and a valve mounted in the pivotal support for axial movement for controlling the flow of air through the said ducts.

59. The combination, in pneumatic holding and feeding mechanism for tubes, of a tube carrier provided with a plurality of air ducts, a monitor head revolubly supporting the carrier, a pivotal support for the monitor head provided with air ducts communicating with the said air ducts of the carrier when the latter is in its feeding position, and a valve mounted in the pivotal support for axial movement, and provided with means for controlling the plurality of ducts of said tube carrier.

60. The combination, in pneumatic holding and feeding mechanism for tubes, of a movable feeder, a valve controlling the pneumatic action of the feeder, a driving shaft mounted in parallel relation to the tube, and a sliding connection between the shaft and valve.

61. The combination, in pneumatic holding and feeding mechanism for tubes, of a movable feeder, a valve for controlling the pneumatic action of the feeder, a driving shaft mounted in parallel relation to the tube, and a valve arm connected with the valve and mounted for sliding movement on the shaft.

62. The combination, in pneumatic holding and feeding mechanism for tubes, of a movable feeder for the tubes, a valve movable with the feeder for controlling the pneumatic action thereof, a driving shaft mounted in a parallel relation to the tube, a valve arm connected with the valve and mounted for sliding movement on the shaft, means for moving the feeder and means for rocking the shaft.

63. The combination, in pneumatic holding and feeding mechanism for tubes, of a feed bar, tube feeding mechanism mounted for sliding movement on the said feed bar, means for imparting longitudinal movements to the bar, and means for varying the amplitude of the said longitudinal movement for the different amounts of feed desired.

64. The combination, in pneumatic holding and feeding mechanism for tubes, of a feed bar mounted for longitudinal movement, tube feeding mechanism mounted for longitudinal movement relative to the bar, means for moving the bar longitudinally,

and a variable connection between the said bar and its moving means for varying the amplitude of its longitudinal movement.

65. The combination, in pneumatic holding and feeding mechanism for tubes, of a feed bar, tube feeding mechanism, supported by and movable longitudinally of the bar, a feed lever, means for swinging the lever, and an adjustable connection between the feed lever and the feed bar, to vary the amplitude of movement of the feed bar.

66. The combination, in tube feeding mechanism, of a receiver for the tube, a tube feeder, means for supporting the tube feeder with the latter projecting into co-active relation with the receiver, including a supporting head mounted for sliding movement to facilitate the longitudinal withdrawal of the tube feeder from the receiver.

67. The combination, in tube feeding mechanism, of a receiver for the tube, a tube feeder, means for supporting the tube feeder with the latter projecting into co-active relation with the receiver, including a supporting head mounted for sliding movement to facilitate the longitudinal withdrawal of the tube feeder from the receiver, and means for locking the said head in co-active relation to the receiver.

68. The combination, in tube feeding mechanism, of a receiver for the tube, a tube feeder, a head supporting the tube feeder, and means for moving the said head to impart the feeding movements of the feeder, the said head being mounted for sliding movement to enable the tube feeder to be retracted from the receiver independently of its feeding means.

69. The combination, in tube feeding mechanism, of a receiver for the tube, a tube feeder, a head supporting the tube feeder and mounted for longitudinal movement relative to the tube, pneumatic pressure devices carried by the said head, a valve also carried by the said head for controlling its pneumatic action, means for imparting longitudinal movement to the feeder and its head, and means for operating the valve during the said longitudinal movements, including a driving shaft journaled in substantially parallel relation to the tube, and having a sliding driving connection with the valve.

70. The combination, in tube feeding mechanism, of a receiver for the tube, a tube feeder, a head supporting the tube feeder and mounted for longitudinal movement relative to the tube, pneumatic pressure devices carried by the said head, a valve also carried by the said head for controlling its pneumatic connection, means for imparting longitudinal movement to the feeder and its head, means for operating the valve during the said longitudinal movements, including a driving shaft journaled in substantially

- parallel relation to the tube, and having a sliding driving connection with the valve, and means for operating the said driving shaft.
- 5 71. The combination, in the tube feeding mechanism, of a pneumatic gripper for the tube, and means for operating the gripper by applying exhaustion and super-atmospheric pressure in alternation thereto.
- 10 72. The combination, in tube feeding mechanism, of a pneumatic gripper provided with an air duct, and means for alternately exhausting the said duct and applying super-atmospheric pressure thereto.
- 15 73. The combination, in tube feeding mechanism, of a pneumatic gripper provided with two independent air ducts, and means for exhausting one duct and applying super-atmospheric pressure to the other duct.
- 20 74. The combination, in tube feeding mechanism, of a pneumatic gripper provided with a plurality of air ducts, and means for exhausting one of said ducts and directing super-atmospheric pressure to another of said ducts.
- 25 75. The combination, in tube feeding mechanism, of a pneumatic gripper provided with a plurality of air ducts, means for exhausting one duct and directing super-atmospheric pressure to another duct, and means for reversing the said action relative to the two ducts.
- 30 76. Means for feeding tubes, including a pneumatic gripper provided with a plurality of air ducts, means for exhausting one of said ducts and directing super-atmospheric pressure to another of said ducts, and means for reversing the said action, applying the exhaustion and the super-atmospheric pressure alternately to the two ducts and in alternation with each other.
- 35 77. Means for feeding tubes, including a tube receiver and feeder provided with pneumatic holding mechanism for the tube, including means for applying exhaustion and super-atmospheric pressure alternately to the said holder and feeder.
- 40 78. Means for feeding tubes, including in combination a receiver for one wall of the tube, a feeder for another wall of the tube, and means for applying exhaustion and super-atmospheric pressure to the respective walls of the tube in alternation with each other.
- 45 79. Means for feeding tubes, including in combination a receiver for one side of the tube wall a feeder for the other side of the tube wall, and means for applying exhaustion and super-atmospheric pressure in alternation with each other and alternately with respect to the two sides of the wall.
- 60 80. Means for feeding tubes, including in combination a receiver for the exterior wall of the tube, and a feeder for the interior wall of the tube, each provided with a pneumatic duct, means for exhausting air through the duct from the exterior wall of the tube, while applying super-atmospheric pressure to the inner wall of the tube to hold the tube against the receiver, and means for reversing this action, exhausting the air from the interior of the wall while applying the super-atmospheric pressure to the outer side of the wall to hold the tube to the feeder.
- 65 81. Means for feeding tubes, including in combination a receiver for the exterior wall of the tube, and a feeder for the interior wall of the tube, each provided with a pneumatic duct, means for exhausting air through the duct from the exterior wall of the tube while applying super-atmospheric pressure to the interior wall of the tube to hold the tube against the receiver, means for reversing this action, exhausting the air from the interior of the wall while applying super-atmospheric pressure to the outer side of the wall to hold the tube to the feeder, and means for advancing the feeder while the tube is thus held to it.
- 70 82. Means for feeding tubes, including in combination a receiver for the exterior wall of the tube, and a feeder for the interior wall of the tube, each provided with a pneumatic duct, means for exhausting air through the duct from the exterior wall of the tube while applying super-atmospheric pressure to the interior wall of the tube to hold the tube against the receiver, means for reversing this action, exhausting the air from the interior of the wall while applying the super-atmospheric pressure to the outer side of the wall to hold the tube to the feeder, and means for moving the feeder to advance the tube while the latter is thus held to the feeder, and means for retracting the feeder when the tube is held to the receiver.
- 75 83. The combination, in tube feeding means, of a rotary receiver for the exterior of the tube, a rotary plunger for the interior of the tube, pneumatic pressure producing means including exhausting and air compressing mechanism, air passages communicating from the said pressure producing means to the tube engaging surfaces of the receiver and the plunger, respectively, and means for controlling the said communication to establish a partial vacuum on one side of the wall of the tube and super-atmospheric pressure on the other side of the wall.
- 80 84. The combination, in tube feeding mechanism, of supporting and feeding devices engaging with the outer and inner surfaces, respectively, of the tube, pneumatic pressure producing means including exhaust and air compressing mechanism, and means for establishing exhaust communication with

one surface of the tube coincidently with the establishment of pressure communication with the other surface of the tube.

85. The combination, in tube feeding mechanism, of supporting and feeding devices engaging with the outer and inner surfaces, respectively, of the tube, pneumatic pressure producing means including exhaust and pressure mechanism, and means for establishing exhaust communication alternately with the inner and outer surfaces of

the tube, and coincidently with the establishment of pressure on the other surface of the tube.

In testimony whereof I have signed my ¹⁵ name to this specification in the presence of two subscribing witnesses.

WM. H. HONISS.
